UNITED STATES PATENT OFFICE.

EPHRON CATLIN, JR., OF ST. LOUIS, MISSOURI, ASSIGNOR OF ONE-HALF TO
HUNTINGTON SMITH, JR., OF ST. LOUIS, MISSOURI.

LIQUID-CONTAINER.

1,075,762.

Specification of Letters Patent.

Patented Oct. 14, 1913.

Application filed October 31, 1912. Serial No. 722,866.

To all whom it may concern:

Be it known that I, EPHRON CATLIN, Jr., a citizen of the United States, residing in the city of St. Louis and State of Missouri, have invented a new and useful Liquid-Container, of which the following is a specification.

This invention relates to liquid containers, and it consists of the novel construction, 10 combination and arrangement of parts hereinafter illustrated, described and claimed.

The invention has particular reference to closures for containers, and an object is to provide a container having a single outlet 15 passage, in combination with means for preventing the insertion of liquids into the container through said outlet passage, said parts being of a novel construction and arrangement.

20 Another object is to provide, in combination with the outlet passage of a liquid container, a valve permitting egress of the liquid from within the container and adapted to prevent insertion of liquids into said 25 container, and a shield or guard arranged to prevent manipulation of said valve for purposes of refilling the container.

A further object is to provide, in combination with the outlet passage of a container, a valve adapted to permit egress of the liquids from the container and to prevent refilling said container, a guard preventing manipulation of said valve, and locking means preventing removal of said 35 parts.

Other objects will appear from the following detailed description, reference being made to the accompanying drawings in which I have illustrated one embodiment 40 of my invention, and in which—

Figure 1 is a vertical sectional view of a portion of a liquid container having my invention mounted in combination therewith, parts of my invention being also shown in 45 section. Fig. 2 is a cross sectional view taken approximately on the line 2—2 of Fig. 1. Fig. 3 is a sectional view showing the valve guard or shield in section, and a separate holder or latch for said guard or shield, said parts being shown in a single integral structure in Fig. 1. Fig. 4 is an inverted view of the valve guard or shield. Fig. 5 is an inverted view of the pivoted valve detached from the coöperating parts. 55 Fig. 6 is a plan view of the valve support.

In the embodiment shown, 1 indicates a portion of a liquid container having an outlet passage 2 in the form of a tubular extension, and provided near its base with an internal flange or rib 3. The outer or 60 discharge end of the outlet passage 2 is provided with external encircling ribs or flanges 4.

The parts comprising my invention are used in connection and combination with 65 the outlet passage 2 of the container, and may include a tubular layer 5 of cork or other suitable material constituting a hermetic seal between the inner surface of the passage 2 and the solid elements included 70 in my invention. The said layer 5 preferably extends from the discharge end of the passage 2 to the upper surface of the internal rib or flange 3. A valve support 6, which may be composed of glass or other 75 preferred material, rests upon the rib or flange 3, the layer 5 forming a hermetic seal between said flange support and the inner surface of the passage 2. The valve support 6 is provided with an opening 7, 80 which is enlarged and dished at its upper portion as indicated at 8.

A tubular valve guard or shield 9 rests upon the upper surface of the valve support 6. Said guard or shield is provided, near 85 one side thereof, with a recess or depression 10, which constitutes a bearing for the projections 11 of a disk valve 12. Said valve 12 being pivoted by the projections 11 operates within the dish 8, and constitutes a 90 closure for the passage 7 to prevent the flow of liquids into the container. The lower or inner part of the valve 12 projects into the passage 7 when said valve is seated, while the upper rim portion of the valve rests 95 upon the flange separating passage 7 from the dish or enlarged portion 8. Upward movement of the valve is limited by projections 13 on the inner side of the shield or guard 9, thereby preventing movement of 100 said valve upwardly into the said guard or shield. Thus it will be seen that the container cannot be positioned so that the valve will be retained open during inward flow of liquid, but should it be attempted to force liquid into the container in any position of the container, the said valve will be forced to its seat within the dish 8, thereby closing the passage into the container and preventing the entrance of the liquid. The 110

guard or shield 9 is provided with a plurality of oblique openings 14 through which the liquid may pass outwardly from the container. The said openings being arranged obliquely as shown and described prevent manipulation of the valve by wires or other operating devices, so that it will be impossible to hold the valve open manually, because no engagement can be made with said valve.

10 The guard or shield 9 may be formed integral with a tubular element 15, as shown in Fig. 1, or the said valve may be a separate part, as shown in Fig. 3. If made separately the inner end of the tubular part 15 will rest upon the flange around the lower end of the guard or shield thereby firmly holding said guard or shield in position and preventing removal thereof. The upper or 20 outer extremity of the tubular member 15 is provided with an external flange 16 which extends across the outer end of the sealing layer 5 and presses against the outer end of the passage 2.

25 Under many conditions I prefer to employ a seal 17 encircling the outer end of the passage 2, interlocked with the ribs or flanges 4, and extending over the flange 16, thereby constituting a lock or seal to prevent removal of any of the parts. Said lock or seal 17 is preferably provided with the central opening of dimensions equal to or larger than the dimensions of the passage through the tubular part 15 in order 30 to permit insertion and removal of a stopper 18, which may be of cork or other suitable material.

I prefer not to rely entirely upon the external seal 17 as a means of preventing removal of the parts. The tubular part 15 40 may be provided with an internal flange 19 with a recess 20, adapted to register with a similar recess 21 in the inner side of the passage 2, when the parts are finally positioned after the container has been filled. The recess 20 contains a spring 22 and a lock bolt 23 preferably of such a length that it may press entirely into the recess 20, so 45 that after the lining or layer 5 has been positioned the bolt 23 may be pressed into the said recess 20 and the tubular element 15 within said lining or layer 5 to its final position, at which time the recess 20 registers with the recess 21, as above explained. 50 When said recesses are brought into registering relation the spring 22 expands and presses the bolt 23 outwardly into the recess 21, said bolt being of such a length that its outer end may rest against the outer 55 wall of the recess 21, while its inner end rests within the recess 20, thereby firmly locking the tubular retaining element 15 in its adjusted position and preventing removal of any of the parts. It will be seen 60 that the external flange 16 extending en-

70 tirely across the outer end of the layer 5 will prevent access to and removal of said layer, so that it is impossible to manipulate any of the parts in a way not intended and thereby effect a refilling of the container.

I have shown a portion of a glass container with a valve support 6, the valve guard or shield 9, and the retaining tube 15, composed of glass, but it is obvious that any preferred material adapted for these purposes may be utilized in the place of glass.

75 It will be apparent that there may be variations from the precise construction and arrangement illustrated and described, without the slightest departure from the spirit and scope of my invention, and I do not restrict myself to identical features of construction or arrangement.

80 What I claim and desire to secure by Letters Patent of the United States is:

85 1. The combination with the outlet passage of a container, of a valve support within said outlet passage, a guard provided with an imperforate top, a valve resting upon said valve support, projections on said 90 valve extending between said support and said guard, oblique passages whose outer ends are lower than their inner ends opening through the side wall of said guard, a tube in said outlet passage encircling said 95 guard, and elements locking said tube in position, substantially as specified.

2. The combination with the outlet passage of a container, of a stationary support 100 mounted in said passage, a guard above said stationary support, a valve above said support, projections on said valve engaging said stationary support, means preventing said valve from entering said guard, a tube encircling said guard and forming a space between said tube and said guard, passages 105 through the wall of said guard arranged to discharge the contents of said container into said space, and elements locking said tube within said outlet passage of the container, 110 substantially as specified.

3. The combination with the outlet passage of a container, of a valve within said outlet passage, means supporting said valve in an oblique position, an inverted cup-shaped guard above said valve and having an imperforate top, oblique passages through the side wall of said guard, an abutment in said guard below said passages preventing movement of said valve into said guard 115 when the container is inverted, and a lock device mechanically locking said guard within said outlet passage, substantially as specified.

4. The combination with the outlet passage of a container, of a support in said passage having a dished recess in its upper side, a valve resting in said recess and having one edge pivoted above said support, an inverted cup-shaped guard seated on said support, 120

said guard being provided with an imperforate outer end wall, passages extending obliquely outwardly and downwardly through the side wall of said guard, means preventing movement of said valve beyond a substantially horizontal position when the container is inverted, a tube in said outlet passage encircling said guard, a lock device holding said tube within said outlet passage of the container, and a layer of elastic material between said tube and said outlet passage, substantially as specified.

5. The combination with the outlet passage of a container, of a support in said passage having an enlarged recessed valve seat in its upper side, a valve seated in said valve seat, projections on said valve resting on the upper side of said support, an inverted cup-shaped guard in said passage

10 provided with an imperforate outer end, passages opening obliquely downwardly and outwardly through the wall of said guard, means retained in position by said guard to prevent movement of said valve beyond a

15 horizontal position when the container is inverted, and a seal encircling said outlet pas-

sage and holding said guard in position within said outlet passage, substantially as specified.

6. The combination with the outlet passage of a container, of a stationary support in said passage having an oblique valve seat in its upper side, an inverted cup-shaped guard resting against said support, a valve seated on said valve seat, projections on said valve extending between said support and said guard, means within said guard for preventing movement of said valve into said guard when the container is inverted, passages opening obliquely downwardly and outwardly through the wall of said guard, and locking elements holding said guard in position within said outlet passage, substantially as specified.

In witness whereof, I have signed this 45 specification in the presence of two subscribing witnesses.
